PROTECTION AGAINST MOMENTARY LOSS OF TRACK CIRCUIT SHUNT

Arthur E. Dodd, Edgewood, Pa., assignor to Westinghouse Air Brake Company, a corporation of Pennsylvania

Application January 27, 1951, Serial No. 208,118 10

10 Claims. (Cl. 246—34)

My invention relates to protection against momentary loss of track circuit shunt. More particularly, my invention relates to apparatus for preventing false operation of railway traffic controlling apparatus due to a momentary loss of track circuit shunt.

Track circuit control of railway traffic controlling apparatus, such, for example, as signals and track switches, is based on the principle that when a train or other railway vehicle enters upon a track section, the rails of which are included in a track circuit in series with a track relay, a plurality of shunt paths, one through each pair of wheels and the associated axle, will be completed across the track circuit; and that such shunting of the track circuit will be effective to deenergize the track relay so that its front contacts will become opened and its back contacts will become closed, and will remain in that condition as long as any one of the pairs of wheels remains on the track section. It has been found, however, that under some conditions such, for example, as when the rails have become rusty or when there is some material such, for example, as sand on the rails, there may be a momentary loss of shunt of the track circuit so that the track relay may become energized and open its back contacts and close its front contacts while one or more pairs of wheels remain on the track section.

A railway signal for governing traffic movements over such a track section, particularly if it is of a quick-acting type such, for example, as a light signal, if controlled directly by a front contact of the track relay, might therefore display a proceed indication for a brief period of time during a momentary loss of shunt of the track circuit. Obviously, it would be a dangerous condition if a signal for a track section displayed a proceed indication for even a brief period of time while the associated track section is occupied by a car or train.

An object of my invention, therefore, is to provide protection against momentary loss of track circuit shunt, so that a signal for governing traffic movements over an associated track section will not be controlled to display a proceed indication, or some other traffic controlling apparatus for the track section, such, for example, as a track switch, will not be falsely operated, because of a momentary loss of track circuit shunt.

A feature of my invention for attaining this object is the provision of a first repeater relay, arranged to be slow releasing, controlled by a back contact of a track relay, a second repeater relay, which may be of a slow pickup type, having a pickup circuit controlled by a front contact of the first repeater relay, and having a stick circuit controlled by a front contact of the track relay and by a front contact of the second repeater relay, and traffic governing means controlled by a back contact of the first repeater relay and by a front contact of the second repeater relay.

Another feature of my invention for attaining this object, in an arrangement in which a first or back contact repeater relay for a track relay is rendered slow re-

2

leasing by an energy storing device connected in multiple with the control winding of the first repeater relay, is the provision of a second repeater relay, which may be of the slow pickup type, having a make-before-break front and back contact, and having stick and pickup circuits controlled by the make-before-break contact and by front contacts of the track relay and the first repeater relay, and the provision of control means for a traffic governing device including a back contact of the first repeater relay and a front contact of the second repeater relay.

I shall describe one form of apparatus embodying my invention, and shall then point out the novel features thereof in claims.

The accompanying drawing is a diagrammatic view showing one form of apparatus embodying my invention, in an arrangement having a slow releasing first or back contact repeater relay TPB for a traffic responsive relay such, for example, as a track relay TR, which includes a second repeater relay TP, of the slow pickup type, having a make-before-break contact 10, which includes stick and pickup circuits for the second repeater relay controlled by front and back points of the make-before-break contact and by front contacts of the track relay and the first repeater relay; and which include traffic governing means such, for example, as a signal 1S, controlled by a back contact 11 of the first repeater relay and by a front contact 12 of the second repeater relay.

Similar reference characters refer to similar parts in the drawing.

Referring further to the drawing, a stretch of railway track is shown, over which trains may normally move in either direction. Rails 3 and 3a of the stretch of track are divided by insulated joints 4 to form a track section T. Section T is provided with a track circuit which includes rails 3 and 3a of the section and a suitable source of current such, for example, as a secondary winding d of a track transformer, designated by the reference character F, connected across the rails adjacent one end of the section, and also a track relay TR connected across the rails adjacent the opposite end of the section.

A signal, designated by the reference character 1S, is located adjacent the relay end a of section T, for governing traffic movements over section T toward the right, as shown in the drawing, which I shall assume is the eastbound direction. A second signal, designated by the reference character 2S, is located adjacent the opposite end b of section T for governing traffic movements in the opposite or westbound direction over section T. Signals 1S and 2S may be of any suitable design such, for example, as the well-known color light or searchlight type.

A first, or back contact, repeater relay, designated by the reference character TPB, is controlled by a back contact of track relay TR. Relay TPB is made slow releasing by a resistor, designated by the reference character r, and an energy storing device shown as a capacitor, designated by the reference character c, connected in series with each other around the winding of relay TPB. Relay TPB and capacitor c are at times energized, in multiple with each other, by current from a suitable source, such, for example, as a battery Q, having a positive terminal B and a negative terminal N.

A second, or front contact, repeater relay, designated by the reference character TP, is of a slow pickup type, and operates a contact 10 of a well-known form known as a make-before-break, or continuity, contact, which is closed at a back point, while relay TP is deenergized, and which becomes closed at a front point before becoming opened at the back point, when relay TP becomes energized.

A pickup or energizing circuit, which may also be referred to as an operating circuit, for relay TP includes

its control winding, and is supplied with energizing current from capacitor *c* through resistor *r*, through front contacts 8 and 9 of relays TR and TPB, respectively, and through the back point of contact 10 of relay TP. A stick, or retaining, circuit for relay TP includes its control winding, and is supplied with energizing current passing from battery Q, through the front point of a contact 7 of relay TR, and through the front point of contact 10 of relay TP.

Alternating current is supplied by a suitable source such, for example, as an alternating current generator, designated by the reference character G, over a pair of line conductors or terminals, designated by the reference characters BX and NX. The primary winding *m* of track transformer F is energized by current from terminals BX and NX.

It is obvious that direct current may be applied directly to the rails 3 and 3a from a suitable source of direct current in which case transformer F would be omitted.

As here shown, track relay TR is of a two-element alternating current type, having a track winding connected to the rails 3 and 3a of section T, and having a line control winding *h*. Line control winding *h* is energized by current from terminals BX and NX over contact 5 of relay TR or over contact 6 of relay TPB. It is obvious to anyone skilled in the art that a direct current relay may readily be used in place of the two element alternating current relay shown if the track circuit is energized from a direct current source.

The purpose of this control of line control winding *h* of relay TR is to prevent a locked-out condition of relay TP, in the event of a partial shunt of track section T which, on account of relay TR being of an alternating current type, might cause contact 7 of relay TR to become opened at its front point, deenergizing relay TP, and to then float for a brief period of time between its front and back points, and to then again become closed at its front point without becoming closed at its back point. If contact 7 of relay TR did not become closed at its back point after becoming opened at its front point and thereby deenergizing relay TP, relay TPB would not become energized, and relay TP would therefore remain deenergized after relay TR again became energized.

The phenomenon of "floating" occurs only under a relatively restricted combination of conditions which rarely occur together so that a single winding relay could be used but I prefer to employ a two winding relay with an alternating current track circuit to avoid any possibility of a locked-out condition.

A circuit for controlling signal 1S to normally display a proceed indication includes a back contact 11 of relay TPB and a front contact 12 of relay TP. A circuit for controlling signal 2S to normally display a proceed indication, similarly includes a back contact 13 of relay TPB and a front contact 14 of relay TP.

Having described, in general, the arrangement and control of the various parts of apparatus embodying my invention, I shall now describe the circuits and operation in detail.

As shown in the drawing, all parts are in the normal condition, that is, track section T is unoccupied, and therefore track relay TR is energized; relay TP is energized by its retaining circuit; relay TPB is deenergized; capacitor *c* is in the discharged condition; and signals 1S and 2S are displaying a proceed indication.

A stick circuit, by which the line control element or winding *h* of relay TR is energized, passes from terminal BX, through contact 5 of relay TR, and winding *h* of relay TR to terminal NX.

I shall assume that, with apparatus embodying my invention, as shown in the accompanying drawing, an eastbound train passes signal 1S onto track section T, deenergizing relay TR. With relay TR deenergized, its contact 5 will be open in the circuit previously traced for winding *h* of relay TR.

With relay TR deenergized, the retaining circuit for relay TP will be opened at the front point of contact 7 of relay TR, so that relay TP will be deenergized and its contacts 12 and 14 will open the circuits for signals 1S and 2S, respectively, causing signals 1S and 2S to cease to display a proceed indication. With relay TR deenergized, relay TPB will become energized by a circuit passing from terminal B, through the back point of contact 7 of relay TR, the winding of relay TPB in multiple with a path through resistor *r*, and capacitor *c*, to terminal N.

When relay TPB becomes energized, a pickup circuit will be completed for winding *h* of relay TR, this circuit passing from terminal BX, through contact 6 of relay TPB, and winding *h* of relay TR to terminal NX. Relay TR will, however, not become operated, for opening its back contact and closing its front contacts, as long as track section T is occupied by the train.

When the train leaves section T, relay TR, on account of its pickup circuit just traced being completed, will again become energized, thereupon opening the circuit traced for relay TPB, at the back point of contact 7.

Relay TPB is, however, slow releasing, on account of resistor *r* and capacitor *c* being connected around its control winding, and therefore relay TPB will not at once release its contacts 9, 11 and 13 to permit contact 9 to open and contacts 11 and 13 to close. During the release period of relay TPB, while contact 9 of relay TPB remains closed, relay TP will become energized by a pickup circuit passing from capacitor *c*, through resistor *r*, contacts 8 and 9 of relays TR and TPB, respectively, contact 10 of relay TP closed at its back point, the winding of relay TP, and terminal N back to capacitor *c*. Contact 10 of relay TP will then start to move from its back point toward its front point.

Before contact 10 becomes opened at its back point, it will become closed at its front point, thereby completing, for a brief period of time, a second energizing circuit for capacitor *c* and relay TPB, this circuit passing from terminal B, through the front point of contact 7 of relay TR, front point of contact 10 of relay TP, back point of contact 10 of relay TP, contact 9 of relay TPB, contact 8 of relay TR, and winding of relay TPB connected in multiple with the path through resistor *r* and capacitor *c* to terminal N. This second energizing circuit for relay TPB and capacitor *c* serves to increase the release period for relay TPB.

When contact 10 of relay TP becomes closed at its front point, the stick circuit will be completed for relay TP, this circuit passing from terminal B, through the front point of contact 7 of relay TR, the front point of contact 10 of relay TP, and the winding of relay TP to terminal N.

At the end of the release period of relay TPB, its contacts 6 and 9 will become open, and its contacts 11 and 13 will become closed. With contact 6 open, the pickup circuit previously traced for winding *h* of relay TR will be opened, but the stick circuit for winding *h* through contact 5 of relay TR will then be closed, so that relay TR will remain energized. With contact 9 of relay TPB open, the pickup circuit for relay TP will be open at contact 9 as well as at the back point of contact 10 of relay TP, but relay TP will then remain energized by its stick circuit previously traced. The release period for relay TPB may be arranged to be of the order of 15 seconds, during which relay TP will become operated and complete its stick circuit.

With relay TP again energized, and relay TPB again deenergized, the circuits previously described for controlling signals 1S and 2S to display a proceed indication will again be completed.

As I have already stated, relay TPB is made slow releasing by resistor *r* and capacitor *c* connected in series with each other around the winding of relay TPB, and also by the circuit closed through the front and back points of contact 10 of relay TP while contact 10 of

relay TP is moving from its back to its front point. The values of resistor r and capacitor c and the length of the pickup time of relay TP may be selected so that the release time of relay TPB may, for example, be of the order of 15 seconds.

Relay TP, on account of its pickup circuit being controlled by a front contact of relay TPB, checks that relay TPB is not disconnected from its energizing circuit. Relay TP, on account of being energized by capacitor c , checks that capacitor c is not disconnected and that it has not become defective. If capacitor c should become disconnected or should become defective, relay TP would not receive sufficient energy from capacitor c to cause relay TP to pick up. Furthermore, if capacitor c should become disconnected or defective, relay TPB would release so quickly that there would not be time for relay TP to pick up. Relay TP, therefore, also checks that relay TPB has a sufficiently long release period to bridge a momentary loss of track circuit shunt, so that signals 1S and 2S cannot become falsely operated to display a proceed indication because of a momentary loss of shunt of track section T. On account of signals 1S and 2S being controlled by front contacts of relay TP, the pickup circuit of which is controlled by a front contact of relay TPB, these signals cannot be controlled to display a proceed indication if relay TPB should become disconnected and therefore remain deenergized.

I shall now assume that, with apparatus arranged as shown in the drawing, an eastbound train enters section T, deenergizing relay TR and thereby causing relay TPB to become energized, as previously described. I shall assume further that there is a momentary loss of shunt of the track circuit for section T, so that relay TR picks up for a brief period of time. Relay TP, being of the slow pickup type, will not close its front contacts until after the lapse of a measured period of time, during which the track shunt will probably be again restored. If, however, the loss of shunt should be long enough for relay TP to close its stick circuit through the front point of contact 10, relay TPB would still retain its contact 9 closed and its contacts 11 and 13 open, and would therefore bridge any momentary loss of shunt. The circuits for signals 1S and 2S would therefore remain open at the back contacts 11 and 13, respectively, of relay TPB, and at the front contacts 12 and 14, respectively, of relay TP, or at only the back contacts 11 and 13 of relay TPB during a momentary loss of shunt.

It follows that, in apparatus embodying my invention, signals 1S and 2S would not be controlled to display a proceed indication falsely because of a momentary loss of shunt of track section T. Apparatus embodying my invention therefore provides protection against false operation of railway traffic controlling apparatus, such, for example, as a railway signal, during momentary loss of shunt of a track circuit over which the signal governs traffic movements.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a railway traffic controlling arrangement, in which a first repeater relay is controlled by a track relay in the deenergized condition and is rendered slow releasing by an energy storing device connected in multiple with the control winding of said first repeater relay, the combination comprising, a second repeater relay of the slow pickup type having a make-before-break contact which is closed at a back point while the corresponding relay is deenergized and which becomes closed at a front point before becoming opened at said back point when the corresponding relay becomes energized,

a pickup circuit for said second repeater relay energized by said energy storing device and including a front contact of said track relay and a front contact of said first repeater relay and also including said make-before-break contact closed at the back point, a stick circuit for said second repeater relay energized by a suitable source of current and including a front contact of said track relay and also including said make-before-break contact closed at the front point, and traffic governing means controlled by a back contact of said first repeater relay and by a front contact of said second repeater relay.

2. In combination, a section of railway track, a track relay having a first and a second winding, a source of alternating current, a track circuit for said section including the rails of said section and the first winding of said track relay and also said source of alternating current, a first repeater relay, an energy storing device, a source of direct current, a circuit energized by said source of direct current and controlled by said track relay in the deenergized condition for energizing said first repeater relay and said energy storing device in multiple with each other, a circuit including a contact of the first repeater relay for energizing the second winding of the track relay, a stick circuit for the second winding of the track relay including a front contact of the track relay, a second repeater relay of the slow pickup type having a make-before-break contact which is closed at a back point while the corresponding relay is deenergized and which becomes closed at a front point before becoming opened at said back point when the corresponding relay becomes energized, a pickup circuit for said second repeater relay energized by said energy storing device and including a front contact of said track relay and a front contact of said first repeater relay and also including said make-before-break contact closed at the back point, a stick circuit for said second repeater relay energized by the source of direct current and including a front contact of said track relay and also including said make-before-break contact closed at the front point, and traffic governing means controlled by a back contact of said first repeater relay and by a front contact of said second repeater relay.

3. In combination, a stretch of railway track, a source of current, a traffic responsive relay normally energized by said source of current while said stretch of track is unoccupied and becoming deenergized in response to a train occupying said stretch of track, a first repeater relay, an energy storing device, means controlled by said traffic responsive relay in the deenergized condition for effecting energization of said first repeater relay in multiple with said energy storing device, a second repeater relay of a slow pickup type having a make-before-break contact which is closed at a back point while the corresponding relay is deenergized and which becomes closed at a front point before becoming opened at said back point when the corresponding relay becomes energized, a pickup circuit for said second repeater relay energized by said energy storing device and controlled by said track relay and said first repeater relay in an energized condition and by said make-before-break contact closed at its back point, a second source of current, a stick circuit for said second repeater relay energized by said second source of current and controlled by said traffic responsive relay in an energized condition and by said make-before-break contact closed at its front point, and traffic governing means controlled by said first repeater relay in the deenergized condition and by said second repeater relay in an energized condition.

4. In combination, a stretch of railway track, a source of current, a traffic responsive relay normally energized by said source of current while said stretch of track is unoccupied but becoming deenergized in response to a train occupying said stretch of track, a first repeater relay, an energy storing device, means controlled by a back contact of said traffic responsive relay for en-

ergizing said first repeater relay in multiple with said energy storing device, a second repeater relay of a slow pickup type having a make-before-break contact which is closed at a back point while the second repeater relay is deenergized and which becomes closed at a front point before becoming opened at said back point when the second repeater relay becomes energized, a pickup circuit for said second repeater relay energized by said energy storing device and controlled by front contacts of said track relay and said first repeater relay and by said make-before-break contact closed at its back point, a second source of current, a stick circuit for said second repeater relay energized by said second source of current and controlled by a front contact of said traffic responsive relay and by said make-before-break contact closed at its front point, and traffic governing means controlled by a back contact of said first repeater relay and by a front contact of said second repeater relay.

5. In combination, a stretch of railway track, a source of current, a traffic responsive relay normally energized by said source of current while said stretch of track is unoccupied but becoming deenergized in response to a train occupying said stretch of track, a first repeater relay, an energy storing device connected in multiple with said first repeater relay to thereby render the first repeater relay slow-releasing, means controlled by a back contact of said traffic responsive relay for energizing said first repeater relay in multiple with said energy storing device, a second repeater relay of a slow pickup type having a back contact which is closed while said second repeater relay is deenergized and having a front contact which becomes closed before said back contact becomes opened when said second repeater relay becomes energized, a pickup circuit for said second repeater relay energized by said energy storing device and controlled by front contacts of said traffic responsive relay and said first repeater relay and by said back contact of said second repeater relay, circuit means including the front contact of the second repeater relay and the back contact thereof during the time when both said front and back contacts of the second repeater relay are closed for energizing said energy storing device to thereby further increase the release time of the first repeater relay, a stick circuit for said second repeater relay energized by a suitable source of current and controlled by a front contact of said traffic responsive relay and by said front contact of said second repeater relay, and traffic governing means controlled by a back contact of said first repeater relay and by a front contact of said second repeater relay.

6. In combination, a stretch of railway track, a source of current, a traffic responsive relay normally energized by said source of current while said stretch of track is unoccupied but becoming deenergized in response to a train occupying said stretch of track, a slow releasing first repeater relay, an energy storing device, means controlled by said traffic responsive relay in the deenergized condition for energizing said first repeater relay in multiple with said energy storing device, a second repeater relay of a slow pickup type having a back contact which is closed while said second repeater relay is deenergized and having a front contact which becomes closed before said back contact becomes opened when said second repeater relay becomes energized, a pickup circuit for said second repeater relay energized by said energy storing device and controlled by said traffic responsive relay in an energized condition and by said back contact of said second repeater relay, circuit means including said front and back contacts of the second repeater relay in series for energizing the energy storing means, the first repeater relay and the second repeater relay all in multiple; a stick circuit for said second repeater relay energized by a suitable source of current and controlled by said traffic responsive relay in an energized condition and by said front contact of said second repeater relay, and traffic governing means controlled by said first repeater relay in the deenergized

5 condition and by said second repeater relay in an energized condition.

7. In combination, a stretch of railway track, a source of current, a traffic responsive relay normally energized by said source of current while said stretch of track is unoccupied but becoming deenergized in response to a train occupying said stretch of track, a first repeater relay, an energy storing device, means controlled by said traffic responsive relay in the deenergized condition for energizing said first repeater relay in multiple with said energy storing device, a second repeater relay having a back contact which is closed while said second repeater relay is deenergized and having a front contact which becomes closed before said back contact opens when said second repeater relay becomes energized, a pickup circuit for said second repeater relay energized by said energy storing device and controlled by said traffic responsive relay and said first repeater relay in an energized condition and by said back contact of said second repeater relay, a stick circuit for said second repeater relay energized by a suitable source of current and controlled by said traffic responsive relay in an energized condition and by said front contact of said second repeater relay, and traffic governing means controlled by said first and second repeater relays.

20 8. In combination, a stretch of railway track, a source of current, a traffic responsive relay normally energized by said source of current while said stretch of track is unoccupied but becoming deenergized in response to a train occupying said stretch of track, a first repeater relay arranged to be slow releasing, means controlled by said traffic responsive relay in the deenergized condition for controlling said first repeater relay, a second repeater relay of a slow pickup type, a pickup circuit for said second repeater relay controlled by means including front contacts of said traffic responsive relay and of said first repeater relay, a stick circuit for said second repeater relay controlled by front contacts of said traffic responsive relay and of said second repeater relay, and traffic governing means controlled by said first repeater relay in the deenergized condition and by said second repeater relay in an energized condition.

25 9. In combination, a stretch of railway track, a source of current, a traffic responsive relay normally energized by said source of current while said stretch of track is unoccupied but becoming deenergized in response to a train occupying said stretch of track, a first repeater relay arranged to be slow releasing, means including a back contact of said traffic responsive relay for controlling said first repeater relay, a second repeater relay; a pickup circuit for said second repeater relay controlled by means including, in series, front contacts of said traffic responsive relay and of said first repeater relay and a back contact of said second repeater relay; a stick circuit for said second repeater relay controlled by front contacts of said traffic responsive relay and said second repeater relay, and traffic governing means controlled by a back contact of said first repeater relay and by a front contact of said second repeater relay.

30 10. In combination, a stretch of railway track, a source of current, a traffic responsive relay normally energized by said source of current while said stretch of track is unoccupied but becoming deenergized in response to a train occupying said stretch of track, a first repeater relay arranged to be slow releasing, means including a back contact of said traffic responsive relay for controlling said first repeater relay, a second repeater relay, a pickup circuit for said second repeater relay controlled by means including a front contact of said first repeater relay, a stick circuit for said second repeater relay controlled by front contacts of said traffic responsive relay and said second repeater relay, and traffic governing

means controlled by means including a back contact of
said first repeater relay and a front contact of said second
repeater relay.
